UNITED STATES PATENT OFFICE.

CHESTER MCNEIL, OF CHICAGO, ILLINOIS, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,140,753.

Specification of Letters Patent. Patented May 25, 1915.

Application filed December 6, 1909. Serial No. 531,561.

To all whom it may concern:

Be it known that I, CHESTER MCNEIL, a citizen of the United States, residing at Chicago, in the county of Cook, State of Illinois, have invented certain new and useful Improvements in Presser-Feet for Sewing Machines, of which the following is a description, reference being had to the accompanying drawing and to the letters and figures of reference marked thereon.

My invention relates to a presser foot for sewing machines, and particularly to a construction of presser foot which has been devised by me for use in making the imitation buttonhole set forth in my Patent No. 970,094, dated September 13th, 1910. Said imitation button hole is formed by means of a cord or gimp bent between its ends, so that the projecting ribs of the gimp are brought adjacent to each other, and the folded portions of the cord are laid in parallel lines, a sewing machine having two closely spaced needles with a coöperating under thread carrying looper being employed to pass lines of stitches through the projecting ribs, and through the fabric, these stitches being secured by the cross threads of the looper on the under side.

The object of the present invention, is to provide a presser foot for use in connection with such a machine for guiding the gimp, and furthermore, it is desirable to provide for some latitude in the size of the gimp used, and also to provide other features, looking to the making of a neat and finished product.

The invention consists in the various matters hereinafter described, and referred to in the appended claims.

In the drawings: Figure 1 is a front perspective view of so much of a sewing machine, as is necessary to an understanding of my invention, showing the presser foot applied thereto. Fig. 2 is a sectional side view of the presser foot. Fig. 3 is a plan view. Fig. 4 is a detail view of the various parts; Fig. 5 is a cross section of the presser foot showing the gimp in place. Fig. 6 is a plan view of the imitation button hole. Fig. 7 is a detail view of a throat plate having the center guide applied thereto instead of to the presser foot.

In these drawings A represents a portion of the bed of a sewing machine of the Union Special two needle type, the two

needles, a, a, being shown as closely spaced and the loops of thread carried thereby being concatenated on the under surface with a cross thread carried by the looper b.

E' represents the throat plate.

B represents the presser foot forming my invention, the same being provided on its under surface with a channel c, to receive the portions 2, 3, of the cord or gimp, which is folded as at 1, and has projecting ribs.

This presser foot is provided with an opening for the passage of the needles and has secured to the shank, a bent spring plate D,

which has projecting portions d extending down through the needle opening to the bottom of the presser foot, and forming

guards for the needles, and also guides for the outer edges of the gimp, which runs in the channel. Said presser foot has also secured to its upper face a flat spring plate E,

which is secured by the screw e to the presser foot, and by means of the enlarged opening through which the screw passes has a slight adjustment longitudinally. This spring plate has an offset portion f, which

portion f passes down through the slit g in the presser foot, and beyond this portion f is extended downwardly to form a fin or

guide h, which runs between the projecting ribs of the gimp, and at its forward end is guided in the slit g in the front of the presser foot.

It will thus be seen that the fin h forms a vertical yielding tongue or guide extending into the center of the channel or

groove in the bottom of the presser foot and projecting below the bottom of the channel, and also below the side portions of the foot, so that the guide may accommodate itself automatically to different thicknesses of

gimp. This center guide is adjustable in line with the direction of feed to adjust its vertical surface with respect to the needles, in order that different sizes of gimp may be

properly sewed to the material, the back of the fin h fitting in the fold of the gimp; that is, when the folded gimp with the fabric is fed into the machine, the folded over

portion will be drawn against the yielding guide to properly position it with respect to the needles; then the needles sew the folded portion down, and continue to sew the parallel cords.

For the purpose above mentioned, it will be noted that the rear of the fin h which projects downwardly from the portion f is

squared off so as to retain the material back of it. The ends of the plate D which carry the needle guards, are adjustable by means of the screws h.

5. It will be understood, of course, that the center guide instead of being arranged on the presser foot, may be arranged on the throat plate, the body fabric being located above the gimp and the guide. This would 10 necessitate the use of mechanism making two separate rows of stitching.

The throat plate E¹ has a slot g¹. Mounted beneath the throat plate is a spring plate E² which is secured to the throat plate by 15 a screw e¹. This spring plate has a fin or guide h¹ which extends upwardly through the slot and engages and guides the gimp, as above described.

Having thus described my invention, what 20 I claim as new and desire to secure by Letters Patent, is:—

1. In a sewing machine adapted for making imitation buttonholes and the like, stitch-forming mechanism including a pair 25 of closely spaced needles, a presser foot and throat plate, and a vertically arranged center guide attached to one of said elements and located in a plane intermediate of and in advance of the needles with its rear end 30 terminating substantially in the vertical plane including the two needles, whereby the folded gimp for the buttonhole is initially positioned.

2. In a sewing machine adapted for making imitation buttonholes and the like, stitch-forming mechanism including a pair 35 of closely spaced needles, a presser foot and throat plate, and a yielding vertically arranged center guide attached to one of said 40 elements and located in a plane intermediate of and in advance of the needles with its rear end terminating substantially in the vertical plane including the two needles, whereby the folded gimp for the buttonhole 45 is initially positioned.

3. In combination with a sewing machine having stitch-forming mechanism including a pair of closely spaced needles, a presser foot and throat plate and a vertically arranged center guide attached to one of said 50 elements and located in a plane in advance of said needles and extending between them, with means for adjusting said center guide longitudinally.

55 4. In combination with a sewing machine having stitch-forming mechanism, including a pair of closely spaced needles, a presser foot and a throat plate, and a yielding vertically arranged center guide attached to

one of said elements and located in a plane 60 in advance of said needles and extending between them, and means for adjusting said center guide longitudinally with respect to the needles.

5. In combination with a sewing machine 65 having stitch-forming mechanism including a pair of closely spaced needles, a presser foot and throat plate, one of said elements having a longitudinal channel, a vertical guide for the fabric in said channel, and 70 means for adjusting the same longitudinally.

6. In combination with a sewing machine having stitch-forming mechanism, including a pair of closely spaced needles, a presser 75 foot and throat plate, one of said elements having a longitudinal channel, a vertical guide for the fabric in said channel located in a plane in advance of said needles and extending between them, said guide being 80 formed with a squared-off shoulder at the rear substantially in the vertical plane which includes the two needles to position the cord or gimp being sewed.

7. A presser foot having a longitudinal 85 groove or channel, a vertical guide extending into said channel and having also adjustable devices extending down through the presser foot for preventing deflection of the needles and for guiding a cord or gimp. 90

8. In combination with a sewing machine having stitch-forming mechanism including a pair of closely spaced needles, a presser foot having a longitudinal channel for guiding parallel portions of cord or gimp to 95 be sewed, a yielding vertical guide for separating the parallel portions of the cord or gimp, and needle deflection preventing guards extending down through the presser foot and forming a portion of each side wall 100 of the channel.

9. In combination with a sewing machine having stitch-forming mechanism including a pair of closely spaced needles, a presser foot having a longitudinal groove or channel, a vertical yielding center guide extending 105 into said channel, said guide having the rear portion of its guiding edge squared off to retain the fold of the cord or gimp to be sewed substantially in the vertical plane 110 which includes the two needles.

In testimony whereof I affix my signature, in presence of two witnesses.

CHESTER McNEIL.
